UNITED STATES PATENT OFFICE.

FREDERICK J. EDGARS, OF BROOKLYN, NEW YORK.

DESIGN FOR A BOX.

SPECIFICATION forming part of Design No. 23,850, dated December 4, 1894.

Application filed October 31, 1894. Serial No. 527,589. Term of patent 7 years.

To all whom it may concern:

Be it known that I, FREDERICK J. EDGARS, a citizen of the United States, residing at Brooklyn, in the county of Kings and State of New York, have invented and produced a new and original Design for a Wooden Box, of which the following is a specification.

In the drawing I have represented my design by an elevation and partial section.

10 The general configuration of the box is round and the leading features of my design consist in the long plain tapering central portion, the crown shaped top and ribbed and coved base.

15 The design of the cover A comprises the ogee curved top a, the inversely curved ribs

b b', the tapering central rib c and the plain tapering portion d.

The design of the body portion B comprises the tapering plain portion d', a continuation 20 of the plain portion d, the curved bands e e', the curved and tapering rib f, the plain bands g g', the cove h and the rounded base i.

What I claim is—

The design for a wooden box substantially 25 as shown and described.

Signed by me this 29th day of October, A. D. 1894.

FREDERICK J. EDGARS.
